123,654

DESIGN FOR A BROOCH OR SIMILAR ARTICLE

Philip Israel and Theodore C. Steinman,
New York, N. Y.

Application October 12, 1940, Serial No. 95,808

Term of patent 3½ years

To all whom it may concern:

Be it known that we, Philip Israel and Theodore C. Steinman, citizens of the United States of America, residing in the city and State of New York, have invented a new, original, and ornamental Design for a Brooch or Similar Article, of which the following is a specification, reference being had to the accompanying drawing, forming part thereof.

Fig. 1 is a plan view of a brooch or similar article showing our new design.

Fig. 2 is an edge view thereof.

We claim:

The ornamental design for a brooch or similar article, substantially as shown.

PHILIP ISRAEL.
THEODORE C. STEINMAN.
